Primary Examiner — David Muller*Assistant Examiner* — Nathan Johnston(74) *Attorney, Agent, or Firm* — McCarter & English, LLP; David R. Burns(57) **CLAIM**

The ornamental design for an injection tool, as shown and described.

DESCRIPTION

FIG. 1 is a top plan view of an embodiment of our design for an injection tool.

FIG. 2 is a bottom plan view thereof.

FIG. 3 is a right side elevation view thereof, the left side elevation view being a mirror image of the right side elevation view.

FIG. 4 is a front elevation view thereof; and,

FIG. 5 is a rear elevation view thereof.

The broken lines shown throughout these figures depict environmental subject matter only and form no part of the claimed design.
